UNITED STATES PATENT OFFICE.

JAMES S. CAMERON, OF MONTREAL, QUEBEC, CANADA, ASSIGNOR TO WESTERN ELECTRIC COMPANY, INCORPORATED, OF NEW YORK, N. Y., A CORPORATION OF NEW YORK.

CUTTING MACHINE.

Application filed September 24, 1921. Serial No. 502,944.

To all whom it may concern:

Be it known that I, JAMES S. CAMERON, a subject of the King of Great Britain, residing at Montreal, in the Province of Quebec, 5 Dominion of Canada, have invented certain new and useful Improvements in Cutting Machines, of which the following is a full, clear, concise, and exact description.

This invention relates, in general, to cutting machines and more particularly to machines for cutting sheets of material into strips.

The cutting machine hereinafter specifically described is adapted to cut sheets of rubber into strips, although it may be used for other materials having similar properties. It has been found very difficult to cut rubber with edge tools without leaving the edges of the cut jagged and rough, so that 20 when the material is stretched it invariably tears at one of these nicks and is useless for the purpose desired.

It is the object of the invention to provide a machine which will cut sheets of material like rubber into strips of desired width without torn or jagged edges and which shall be inexpensive, simple in construction and reliable in its operation.

These objects are accomplished mainly by 30 the use of heated wires which are stretched across a suitable frame to form a grid and which are electrically heated to the melting point of the material to be cut. The material to be cut is mechanically fed 35 through this grid and the strips cut therefrom are reeled upon spools.

One form which the invention may assume in practice, is shown in the accompanying drawings, in which Fig. 1 shows that portion 40 of the mechanism which provides the motion in the sheet and reels the finished product on spools; Fig. 2 is a side view of the machine showing the grid and the winding spools; Fig. 3 is a perspective showing one form of grid which may be employed 45 and the method of starting a sheet through the machine; and Fig. 4 is a perspective showing the grid and its cooperation with the sheet of rubber in greater detail.

50 Referring to the drawings, a roll of sheet rubber 1 wound on a shaft 2 is supported in a frame having two uprights 3, joined below by lateral braces 5.

55 Supported between uprights 3, by means of plates 48 is a channel member 6. Be-

tween the sides 8 and 9 of the rectangular frame 7 is stretched an electrical conductive wire 10 which passes back and forth. The exposed portions of the wire 10 are parallel and form a grid through which the sheet 60 from the roll 1 is passed to be slit into strips. The width of the strips depends, of course, upon the distance apart of the parallel sections of the wire 10 and this may be changed as desired by substituting a frame provided 65 with a grid having such parallel sections at the desired distances. The wire 10 is connected by the leads 11 and 12 to a suitable source of current (not shown) in circuit with a variable resistance 13 for adjusting 70 the heating current and a switch 14 for opening the circuit. The wire 10 is of a resistance material so that when connected with the source of current, it is heated to a sufficient temperature to melt or cut the sheet of 75 rubber wound on the shaft 2.

The edge 15 of the channel 6 is suitably rounded and smoothed to act as a bearing surface for the sheet of rubber from the roll 1 as it passes through the grid. 80

After passing through the grid, the alternate strips 49 and 50 cut from the sheet of rubber pass over rollers 16 and 17 and are wound on suitable spools 18 and 19 supported on shafts 20 and 21 respectively. The 85 alternate strips 49 and 50 are guided to the rollers 16 and 17 spaced at a considerable vertical distance from each other so that the freshly melted edges of the strips are separated to prevent reuniting. Shafts 20 and 21 and the rollers 16 and 17 are supported on a frame consisting of two uprights 22 and lateral braces 24 and 25. The uprights 3 and 22 are held rigid with respect to each other by means of braces 23. 95

A bracket 26 is formed by a bar bent and bolted to the upright 22. Bracket 26 and an arm 27 also supported by the upright 22, support a vertical shaft 28 upon which is mounted a friction-drive wheel 29 which is 100 slidable vertically on the shaft 28 by means of a shifting device comprising an arm 30 mounted on a screw-threaded shaft 31 which is adapted to be turned by a wheel 32. The friction wheel 29 provides motion to the 105 shaft 19 through a friction wheel 33 mounted on the end thereof and against which the friction wheel 29 bears. Shaft 19 is connected with shaft 20 by means of two sprockets 34 and 35 mounted on the shafts 19 and 110

20 respectively, and connected to each other by a chain 36. Rotation in the shaft 28 is provided through a worm gear 37 associating the shaft 28 with the shaft 38 of an electric 5 motor 39 mounted on the lateral supporting members 24 and 25. A proper regulation of the speed of the rubber sheet through the grid is accomplished by adjusting the bearing point of the friction wheel 29 against 10 the friction wheel 33 by means of the shifting device 30. The motion in the shaft 2 is retarded to produce a proper tension in the sheet of rubber 1 by means of a weight 40 attached to a strip 41 passing over a wheel 15 42 mounted on the shaft 2.

To start the sheet of material through the grid the sheet is placed over the roller 46 and the grid frame is removed from the channel 6 and placed over the sheet so that 20 the wires 10 register in grooves provided in the roller. The sheet is then drawn by its end for a short distance through the grid and cut as indicated at the line 47. The strips may then be passed through the grid 25 in its position in channel 6 and suitably attached to their respective spools for automatic feeding.

What is claimed is:

1. A machine for cutting sheets of rubber 30 or similar material into strips, which comprises a stationary electrically heated grid

and means to draw the sheet through the grid.

2. A machine for cutting sheets of rubber or similar material into strips, which comprises an electrically heated grid through which the sheet is adapted to pass, means to receive the strips severed from the sheet and power-driven means cooperating with said means to draw the sheet through the grid. 35 40

3. A machine for cutting sheets of rubber or similar material into strips, which comprises an electrically heated grid through which the sheet is adapted to pass, means to separate the alternate strips cut from 45 the sheet, a spool for each strip cut from the sheet and means cooperating with the spools to draw the sheet through the grid.

4. A machine for cutting sheets of rubber or similar material into strips, which comprises a grid through which the sheet is adapted to pass consisting of a frame and electrically heated wire stretched there-across, a spool for each of the strips cut from the sheet and a motor provided with 50 55 an adjustable friction drive associated with said spools.

In witness whereof, I hereunto subscribe my name this fourteenth day of September, A. D. 1921.

JAMES S. CAMERON.
